DOOR APPARATUS

Oliver C. Eckel, Boxborough, Mass.

Application October 18, 1952, Serial No. 315,505

6 Claims. (Cl. 20—16)

This invention relates to a swinging door.

One object of my invention is to provide a swinging door with a door mount spaced from the door jamb and with a flexible, sealing member in the clearance space between the door mount and the jamb.

Another object of my invention is to provide said door mount in two parts, spaced apart at one end to permit entrance of a sealing member, which is retained between said parts and a pivot member.

A further object is to provide such a door with a door mount that is simple to install, economical to manufacture, and eliminates the usual metal hinges and pins.

The foregoing and other objects which will appear as the nature of the invention is better understood, may be accomplished by a construction, combination and arrangement of parts such as is disclosed by the drawings. The nature of the invention is such as to render it susceptible to various changes and modifications, and therefore, I am not to be limited to the construction disclosed by the drawings nor to the particular parts described in the specification; but am entitled to all such changes therefrom as fall within the scope of my claims.

In the drawings :

Figure 1 is a front elevational view of my swinging door attached to a jamb, being shown broken away at intermediate and side portions thereof.

Figure 2 is an enlarged sectional view taken on the line 2—2 of Figure 1.

As illustrated, a pivot bearing 10, having an opening 12 therethrough, is shown attached to a door jamb or frame J by screws 14. It is shown in one piece, but could be formed in two halves, split vertically in position of use. These pivot bearings 10 may be located at an upper portion and at a lower portion of the door, and if the door is large there may be one or more located intermediate said upper and lower portions.

Attached to the back surface of the main body 16 of the door is a door mount 18. It has a straight attaching portion 20 and a retaining end portion 22 that is arcuate shaped, as shown. Another door mount 24 is attached to the front surface of said main body 16 and has a straight attaching portion 26 and an end or arcuate portion 27 which extends towards said arcuate portion 22, the two portions being spaced apart as at 28. Screws 29 extend into said attaching portions 20 and 26 and through the main body 16 of the door, thus firmly holding the door mounts 18 and 24 to the door body 16. Said mounts 18 and 24 and the door body 16 have cut-outs 30 at the upper and lower portions to clear the pivot bearings 10. Said mounts are made of relatively firm material, such as $\frac{1}{8}$ inch steel, or aluminum, or plastic.

A pivot member 32 in the form of a pipe extends through said pivot bearing opening 12 and between said door mounts 18 and 24, thus permitting the door to swing freely. Counter-sunk screws 34 pass through said attaching portions 20 and 26 and screw-threadedly connect with said pivot member 32, thus holding the door to the latter.

A wiper or sealing member 36 is made of a flexible

2

material, such as rubber, rubber composition or plastic and usually extends the full height of the door. It has a fin or sealing portion 38 that normally contacts said jamb J at one extremity and extends through the space 28 between said door mount arcuate portions 22 and 27. It also extends in opposite directions from said sealing portion 38 in the form of an arcuate, holding portion 40 which is shown integral with said sealing portion 38. It is firmly held between said pivot member 32 and said door mount arcuate portions 22 and 27, tapering in thickness at both free end portions and terminating before reaching said screws 34. This holding portion 40 is thus held firmly in position as the door is swung open and closed, while said sealing portion 38 seals the clearance space between the door mounts and said jamb J.

What I claim is:

1. Door apparatus in combination with a pivot member, said apparatus comprising a door body, two door mounts each embodying an attaching portion for attachment to said body and an arcuate portion extending from said attaching portion towards each other and terminating at adjacent spaced apart points, means attaching said attaching portions to said door body, said arcuate portions being outside of and adjacent said pivot member, and a sealing member outside said arcuate portions and extending through and beyond said space at both sides of the latter and between a portion of said pivot member and said arcuate portions, and means holding said arcuate portions to said pivot member beyond said sealing member.

2. Door apparatus in combination with a pivot member, said apparatus comprising a door body, two door mounts each embodying an attaching portion for attachment to said body and an end portion extending from said attaching portion towards each other and terminating at adjacent spaced apart points, means attaching said attaching portions to said door body, said end portions being outside of and adjacent said pivot member, and a sealing member outside said end portions and extending through said space and between a portion of said pivot member and said end portions and tapering in thickness towards said door body, and means holding said arcuate portions to said pivot member adjacent the end extremities of said sealing member.

3. Door apparatus in combination with a door jamb to support said apparatus, a pivot bearing attached to said door jamb having an opening therethrough, a door body, two door mounts each embodying an attaching portion attached to said body and an end portion extending from said attaching portion towards each other and terminating at adjacent spaced apart points, a pivot member extending into said pivot bearing opening and between said door mounts, means attaching said door mounts to said pivot member, and a sealing member embodying a flexible sealing portion outside said end portions in contact with said jamb and extending through said space and a holding portion extending from said sealing portion in opposite directions between said door mounts and said pivot member and being held firmly therebetween.

4. Door apparatus in combination with a door jamb to support said apparatus, a pivot bearing attached to said door jamb having an opening therethrough, a door body, two door mounts each embodying an attaching portion attached to said body and an arcuate, end portion extending from said attaching portion towards and adjacent each other and terminating at adjacent spaced apart points, a pivot member extending into said pivot bearing opening and between said door mounts, means attaching said door mounts to said pivot member, and a sealing member embodying a flexible sealing portion outside said arcuate, end portions in contact with said jamb and extending through said space and an arcuate, holding por-

tion extending from said sealing portion in opposite directions between said door mounts and said pivot member and being held firmly therebetween.

5. Door apparatus comprising a door body, two door mounts, a pivot member and two pivot bearings for attachment to a door frame at points spaced apart and each having an opening therein, said pivot member extending into said openings, and beyond said two pivot bearings in a direction between the latter, each said door mount embodying an attaching portion attached to opposite sides of said body and a retaining portion extending laterally from said attaching portion beyond said body and in contact with said pivot member, said pivot member extending between said two retaining portions of each said door mount, and pin means extending into said retaining portions and into the main body portion of said pivot member. 15

6. Door apparatus for use with a door frame, said door apparatus comprising a door body, two door mounts, a pivot member, and two pivot bearings for at- 20

tachment to said frame at points spaced apart and adapted to extend laterally away from said frame and opposite said door body and mounts, each said pivot bearing having an opening therein, said pivot member movably extending into said openings, and beyond said two pivot bearings, in a direction between the latter, each said door mount embodying an attaching portion attached to opposite sides of said body and a retaining portion extending laterally from said attaching portion beyond said body and partly around said pivot member, said pivot member extending between said two retaining portions of each said door mount, and means fixedly attaching said retaining portions directly to the main body of said pivot member.
